UNITED STATES PATENT OFFICE

KARL M. LEDERER, OF NEWARK, NEW JERSEY, ASSIGNOR TO WESTON ELECTRICAL INSTRUMENT CORPORATION, OF NEWARK, NEW JERSEY, A CORPORATION OF NEW JERSEY

RELAY CONTACT

Application filed April 3, 1930. Serial No. 441,411.

This invention relates to relays and more particularly to relay contact elements which are adapted for use in a relay which is sensitively balanced and which is capable of controlling relatively high currents.

An object of my invention is to provide a relay contact element having a buffering member or members, which contact element is simple, strong, inexpensive to manufacture and easily assembled.

A further object is to produce a relay contact element of the type including a resilient buffering member which is capable of carrying a higher current than other control elements of the same general type.

Still another object of my invention is the provision of a contact element in which a buffering member also serves to cause wiping contact between the contact element and the stationary contact members.

Other objects will be apparent from the accompanying drawing and the description thereof, in which drawing:

Fig. 1 is a plan view of the contact element.
Fig. 2 is a side view, partially in cross-section.

Fig. 3 is an oblique view of the auxiliary contact member, and

Fig. 4 is a fragmentary view showing the contact element in one of its closed circuit positions, together with a stationary contact member. The contact element comprises, in its preferred form, two members, a main contact member 1 in the form of a pointer cross and an auxiliary contact member 2.

The main contact member is formed by punching a member of the proper size and shape from a sheet of aluminum or hard drawn sheet copper. It is given the shape of a cross, of which one arm 2 constitutes the pointer or contact arm and the remaining arms 4, 5, 6, constitute balance arms to balance the weight of the pointer arm.

The auxiliary contact member 2 is made from contact material such as platinum, platinum-iridium alloy, silver alloy or equivalent material and is in the form of a channel from which a portion of the web has been removed. This construction provides

a short channel having parallel fingers 7, 8 extending therefrom.

The channeled portion 9 of the auxiliary contact member is secured by means of a rivet 10 to an offset portion 11 of the pointer arm 3 situated substantially midway between the ends of the pointer arm. The web portion of the auxiliary contact member is of such size that the flanges engage the edges of the pointer arm at the offset portion and the fingers extend along opposite sides of the outer portion 12 of the pointer arm. The outer portion 12 of the pointer arm is reduced in size so that there is an appreciable space between the edges of the pointer arm and the sides of the parallel fingers of the auxiliary contact member.

The parallel fingers are made greater in width than the thickness of the pointer arm so that satisfactory contact may be made between them and a cooperating stationary contact member 13. In order that the pointer arm will be disposed symmetrically between the parallel fingers, the offset portion 11 is of such depth as to bring the center of the outer portion of the pointer arm opposite the centers of the parallel fingers (not shown in Fig. 2.) It is obvious that this symmetrical arrangement prevents any twisting of the auxiliary contact member.

When the contact element swings against the stationary contact member 13 (as shown in Fig. 3) one arm 7 of the auxiliary contact member 2 makes wiping contact with the stationary contact member 13 and is forced against the outer end 12 of pointer arm 3, contacting therewith throughout a considerable area, because of the resiliency of the arm of the auxiliary contact member. Current will then flow through the parallel finger 7 and the pointer arm 3.

The parallel fingers 7, 8 being constructed of resilient material, will offer some resistance to the movement of the contact element against the stationary contact member and will thus absorb most of the shock incident to the closing of the contact.

Since the major dimension of the contact element is in its plane of movement, the contact element is relatively rigid and reinforces

the thin contact fingers after it has flexed into engagement with the contact element.

The pointer arm is of relatively large cross-section and a good heat conductor. 5 When it is forced up against one of the parallel fingers and contacts with it through a relatively large portion of the area, any heat which may be developed at the point of contact between the parallel arm and the stationary contact member is absorbed and conducted away and no harmful heating of the contact surfaces is possible.

It is apparent that the invention is particularly useful in the embodiment shown 15 above but is in no way restricted to that use but may be used in any type of single or multiple contact apparatus where it is desired to have a contact member provided with buffering means and capable of carrying relatively high currents.

I claim:

1. In a relay contact element for cooperation with a fixed contact element, the combination with a relatively rigid main member 25 of cruciform shape having one arm reduced in size adjacent the end thereof, of an auxiliary member of flexible material secured to the larger portion of said arm and having a pair of parallel fingers extending along and 30 spaced from the reduced portion of said arm, the end portions of said fingers being disposed to lie against the reduced portion of said arm when said element cooperates with a fixed contact element.
35. 2. In a relay contact element, the combination with an elongated, thin, sheet-metal main member having an offset portion intermediate its ends and a reduced portion adjacent one end, of an auxiliary member of highly 40 flexible material having the form of a channel with a portion of the web removed to provide a pair of parallel fingers, and means for securing the web portion of said auxiliary member to the offset portion of said 45 main member with said fingers extending along and normally spaced from the reduced portion and positioned to contact with the reduced portion when said contact element abuts a stationary contact element, whereby 50 said members mutually reinforce one another.

In testimony whereof, I affix my signature.
KARL M. LEDERER.
